UNITED STATES PATENT OFFICE.

W. L. FISH, OF NEWARK, NEW JERSEY.

ATTACHMENT TO LAMP-CHIMNEYS.

Specification forming part of Letters Patent No. 35,598, dated June 17, 1862; Reissued December 23, 1862, No. 1,368.

To all whom it may concern:

Be it known that I, W. L. FISH, of Newark, in the county of Essex and State of New Jersey, have invented a new and Improved Attachment to Lamp-Chimneys; and I do hereby declare that the following is a full, clear, and exact description of the same, reference being had to the accompanying drawing, forming a part of this specification, in which—

Figure 1: represents a vertical central section of my invention. Fig. 2: is a side elevation of the same.

Similar letters of reference in both views indicate corresponding parts.

This invention consists in the arrangement of a receiver in combination with the chimney of a kerosene or other flame in such a manner that water or other liquid poured into such receiver can be heated by the action of the flame in an easy and convenient manner; it consists further in the arrangement of a window in the lower part of the metal chimney in such a manner that the flame can be observed from the outside and that sufficient light is allowed to pass out into the room to render the device available for a nurse lamp.

To enable those skilled in the art to make and use my invention, I will proceed to describe it.

The chimney A, is made of sheet brass or other suitable conductor of heat and it consists of two parts the bulb a, and the tube b, which are connected so that the tube can easily be taken off without disturbing the bulb which is placed over the flame of a kerosene or other lamp or over a gas flame in the manner as shown in Fig. 1 of the drawing.

B, is the receiver which is constructed of

tinned sheet iron or other suitable material and which is firmly united with the tube b, by soldering or in any other convenient and durable manner. This receiver is placed in such relation to the tube b, that the latter passes clear through its center and a cover c, which is provided with a central hole to pass over the end of the tube, is placed on the receiver. By this arrangement water or other liquid which may be poured into the receiver can be heated in a very short time. The receiver is provided with a handle d, so that the same with the tube b, can be conveniently taken off from the bulb a, when its contents are hot.

The bulb a, is provided with a window e, through which the flame can be observed from the outside and at the same time this window admits some light from the flame into the room so that a lamp with my attachment can be conveniently used as a nurse lamp. This window is in one side of the bulb and it consists of a small aperture covered with mica or other suitable material. By turning the bulb the light emanating from said window can be thrown in any desired direction.

Having thus fully described my invention what I claim as new and desire to secure by Letters Patent is—

1. A lamp chimney A, provided with a receiver B, substantially as and for the purpose shown and described.

2. The arrangement of the window e, in the metal bulb a, of a chimney A, as and for the purpose set forth.

WARREN L. FISH.
